Be it known that I, WILLIAM C. PEET, of Jersey City, in the State of New Jersey, have invented a certain new and ornamental Design 5 for Fire-Places, of which the following is a specification.

In this design the grate-frame, the fender, and the andirons are adapted to the production as a whole of a certain artistic effect.

and scroll ornaments at *o o*, as represented, and there are bead ornaments at *p p*. The 25 andirons are ornamented with a sunflower head, *q*, wing leaves at *r*, round stems *s*, and a square panel with owl and flower ornaments at *t*.

I claim as my invention—

1. The design of the fire-place frame, having 30 the circular ornaments *i k l*, star ornaments *n*, and segment and scroll ornaments *o*, substantially as described and represented.
